UNITED STATES PATENT OFFICE.

LOUIS B. HARVEY, OF STOCKTON, CALIFORNIA, ASSIGNOR TO HARVEY RIM & WHEEL COMPANY, INC., OF BUFFALO, NEW YORK.

DESIGN FOR A DISK WHEEL.

57,776.

Specification for Design.

Patented May 3, 1921.

Application filed February 25, 1920. Serial No. 361,269. Term of patent 14 years.

To all whom it may concern:

Be it known that I, LOUIS B. HARVEY, a citizen of the United States, residing at Stockton, in the county of San Joaquin and State of California, have invented a new, original, and ornamental Design for a Disk Wheel, of which the following is a specification, reference being had to the accompanying drawing, forming a part thereof, in which—

Figure 1 is a side elevation of the wheel and Fig. 2 is a plan view thereof.

I claim:

The ornamental design for a disk wheel as shown.

LOUIS B. HARVEY.
